GARMENT WITH SEMIRAGLAN SLEEVE

Ralph E. Berman, Brooklyn, N. Y.

Application April 11, 1935, Serial No. 15,804

3 Claims. (Cl. 2—93)

This invention relates to new and useful improvements in a garment with a semiraglan sleeve.

The invention has for an object the design and construction of a garment which has all the comfort of a raglan sleeve garment and the appearance of regular seamed shoulders with a substantially straight edge or set-in sleeves.

It is known that a garment with raglan sleeves has narrow sloping shoulders but compensates in greater freedom of motion of the shoulders and arms, elaborating on the two distinct types of shoulders as cut in clothing generally, we have first, what is termed the regular shoulder with the shoulder section being integral with the front and back of garment, and the sleeve sewed or set in circumferentially into the armhole and from the front is substantially straight. Second, we have what is termed a raglan shoulder where the front and back parts of garments are dissected on a line running approximately from the bottom of armhole, front and back, to the point of shoulder at the neck.

It is an object of this invention to design and construct a garment as mentioned which has its parts so arranged and formed that the garment is of set-in sleeve construction in the front and is of raglan sleeve construction in the back.

A still further object of the invention is the construction of material forming the front of the garment so as to have a neck edge continuing into a shoulder seam edge continuing into an edge for one-half of a set-in sleeve, and associated with material in the form of the adjacent rear of the garment having a neck edge continuing into an edge for one half of a raglan sleeve, and a sleeve having half of its rear end curved to fit and be stitched together with said edge for one-half of the set-in sleeve and continuing into a rearward extending edge to fit and be stitched to the said shoulder seam edge, and continuing into a forward extending edge to fit and be attached to said edge for one half of a raglan sleeve.

Another object of the invention is the construction of a garment as described which is simple and durable and which can be manufactured and sold at a reasonable cost.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a garment constructed according to this invention and viewed from the front. 5

Fig. 2 is a rear elevational view of Fig. 1.

Fig. 3 is a plan view of Fig. 1.

Fig. 4 is a developed view of one front quarter of the material of the garment.

Fig. 5 is a developed view of the adjacent rear 10 quarter of the garment.

Fig. 6 is a developed view of one sleeve of the garment.

Fig. 7 is a view similar to Fig. 6 but showing a modified form of sleeve.

Fig. 8 is an other view similar to Fig. 6 but illustrating another modified form of sleeve.

Fig. 9 is a view of the sleeve shown in Fig. 6 partially sewed together with the front quarter of the garment shown in Fig. 4. 20

Fig. 10 is an elevational view of the sleeve shown in Fig. 6 partially sewed together with the rear quarter of the garment illustrated in Fig. 5.

The garment, according to this invention is illustrated in the completed form in Figs. 1-3 25 inclusive. It is composed of front portions 10 having their adjacent edges overlapping and detachably connected with buttons 11 and having their outer edges secured to the outer edges of rear portions 12. These rear portions have their 30 inner edges 13 stitched together. The garment has a collar 14 and sleeves 15. From the front, the garment has regular seamed shoulders produced by shoulder seams 16 and from the rear the sleeves are raglan, indicated by reference 35 numeral 17.

The front portion 10 has a neck edge 14^a to which a portion of the collar 14 is stitched, and this neck edge continues into a shoulder seam edge 16^a which continues into an edge 15^a designed and shaped for receiving one half of a substantially straight or set-in sleeve. The rear portion 12 has a neck edge 14^b to which the collar 14 may be attached, which edge continues into an edge 15^b for one half of a raglan sleeve. 45

The material of the sleeve 15 is shown developed in Fig. 6. Half of the inner end of the sleeve 15 is formed with a curved edge 15^c adapted to fit and be stitched to the edge 15^a of half of the set-in sleeve. The edge 15^c continues into a 50 rearward extending edge 15^d adapted to fit and be attached to the shoulder seam edge 16^a. This edge 15^d continues into a forward extending edge 15^e to fit and be stitched to the said edge 15^b of the one half of the raglan sleeve. 55

In Fig. 9 the sleeve material 15 is shown partially connected with the front portion 10. It should be noted that part of the edge 15^c is stitched to part of the edge 15^a. In sewing this part of sleeve, the material of the sleeve bends under into semitubular shape so that the free portion of the edge 15^c may be stitched to the remaining free edge of the edge 15^a. The edge 15^d of the sleeve material 15 must be stitched to the edge 16^a of the front portion 10.

In Fig. 10 the sleeve material 15 is shown secured together with the rear portion 12. More particularly, the edge 15^e of the sleeve material is stitched to the edge 15^b of the rear portion. The sleeve is also formed by stitching the opposed edges 15^f and 15^g together. From the above description it is believed that the construction of the garment will be readily understood.

In Fig. 7 a modified form of sleeve has been disclosed which is formed from adjacent pieces 15' and 15''. These adjacent pieces have curved edges 15^h and 15ⁱ adapted to be secured together so as to give the sleeve a little fullness at the elbow. In other respects this sleeve construction is identical to the previous described form and the edges thereof may be recognized by the identical reference numerals.

In Fig. 8 another modified form of sleeve is disclosed which is formed from three parts, indicated by reference numerals 25^a, 25^b, and 25^c. The adjacent edges of these parts are shaped so as to enhance the shape of the finished sleeve. In other respects the edges of the sleeve are identical to the edges previously described and similar parts may be recognized by corresponding reference numerals.

The construction of the sleeve forms illustrated in Figs. 7 and 8 may be more economical than the one piece sleeve previously described and make it possible to produce more shapeliness in the finished sleeve.

It is to be understood that it is not necessary to construct this sleeve in a garment with a collar or in a garment with seams either at the front or rear of the garment. This sleeve may be used on garments of all types, sizes, and materials, and the proportions may be changed as desired.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new, and desire to secure by United States Letters Patent is:—

1. In a garment, a semiraglan sleeve construction, comprising material in the form of the front portion of a garment and having a neck edge continuing into a substantially straight appearing shoulder seam edge continuing into a sub-

stantially semicircular edge for one half of a substantially straight appearing edge sleeve, material in the form of an adjacent rear portion of the garment and having a neck edge continuing into a shallow convexed curved edge for one half of a raglan sleeve, and a sleeve having half of its inner end concavely curved to fit and be stitched together with said semicircular edge for one half of a substantially straight appearing edge sleeve and continuing into a substantially straight appearing edge to fit and be attached to the said shoulder seam edge and continuing into a shallow concaved curved edge to fit and be attached to said shallow curved edge for one half of a raglan sleeve.

2. In a garment, a semiraglan sleeve construction, comprising material in the form of the front portion of a garment and having a neck edge continuing into a substantially straight appearing shoulder seam edge continuing into a substantially semicircular edge for one half of a substantially straight appearing edge sleeve, material in the form of an adjacent rear portion of a garment and having a neck edge continuing into a shallow convexed curved edge for one half of a raglan sleeve, and a sleeve having half of its inner end concavely curved to fit and be stitched together with said semicircular edge for one half of a substantially straight appearing edge sleeve and continuing into a substantially straight appearing edge to fit and be attached to the said shoulder seam edge and continuing into a shallow concaved curved edge to fit and be attached to said shallow curved edge for one half of a raglan sleeve, said sleeve being formed from one piece of material having its longitudinal edges attached together to form the tubular sleeve construction.

3. In a garment, a semiraglan sleeve construction, comprising material in the form of the front portion of a garment and having a neck edge continuing into a substantially straight appearing shoulder seam edge continuing into a substantially semicircular edge for one half of a substantially straight appearing edge sleeve, material in the form of an adjacent rear portion of the garment, and having a neck edge continuing into a shallow convexed curved edge for one half of a raglan sleeve, and a sleeve having half of its inner end concavely curved to fit and be stitched together with said semicircular edge for one half of a substantially straight appearing edge sleeve and continuing into a substantially straight appearing edge to fit and be attached to the said shoulder seam edge and continuing into a shallow concaved curved edge to fit and be attached to said shallow curved edge for one half of a raglan sleeve, said sleeve being formed from several longitudinal sections having adjacent edges curved and attached together to make the sleeve form-fitting.

RALPH E. BERMAN.
